UNITED STATES PATENT OFFICE.

EDWARD SULLIVAN, OF STEUBENVILLE, OHIO.

BAR FOR STRINGED INSTRUMENTS.

Application filed July 14, 1922. Serial No. 574,966.

To all whom it may concern:

Be it known that I, EDWARD SULLIVAN, a citizen of the United States, residing at Steubenville, in the county of Jefferson and State of Ohio, have invented certain new and useful Improvements in Bars for Stringed Instruments, of which the following is a specification.

My invention relates to a bar used for 10 playing metallic string instruments, more particularly the Hawaiian guitar, and the object of the invention is to provide a guitar bar that will not wear the strings too rapidly and will produce a more mellow sound 15 on the guitar.

Another object of the invention is to provide a guitar bar of this character which has a steel roller on one side and a straight edge of hard wood on the opposite side. In 20 this manner a metallic sound will be produced when the roller is applied while a softer sound will be the result when the hard wood edge is drawn along the strings.

The guitar steels commonly used are made 25 of solid steel which, when pressed against the strings, will soon cut or destroy the latter, and more particularly the wrapped ones, while this disadvantage is obviated with my device.

30 In the accompanying drawings one embodiment of the invention is illustrated—

Figure 1 is a perspective view of a guitar with the device applied thereon;

Fig. 2 is a perspective view of the guitar 35 bar;

Fig. 3 is a section along line 3—3 of Fig. 2;

Fig. 4 is a fragmentary front elevation;

Fig. 5 is a section similar to Fig. 3, showing 40 a slightly modified form of guitar bar provided with two rollers.

The device consists of a body portion 10 preferably made of fibrous material and of 45 rectangular shape with a thin uniform cross section. On the top of the body portion 10, as seen in the figures, is rigidly secured along the edge thereof, a strip 11 preferably made of hard wood, ebony being most suitable. The top edge of this strip 11 is 50 rounded, while the sides and ends merge into the corresponding sides and ends of the body portion 10 to form a solid connection therewith. The body portion is thickest just below the joint 12 between the same and the strip 11 and tapers slightly downwards as

seen best in Fig. 3, terminating with a slightly hollowed out edge 13 at the bottom.

At each end of the body portion 10 is rigidly secured, by means of screws 14 or the like, a bearing plate 15 in which is revolubly mounted a steel roller which engages with its journals or trunnions 17 in the bearing plates 15, so as to be freely revoluble below the hollowed out edge 13 of the body portion.

The length of the guitar bar is slightly greater than the width across the strings 18 of a guitar 19 and when used the device is held transversely across the strings 18, see Fig. 1, so as to contact with all of them

when drawn upwards along the neck of the instrument.

In case the edge of the device carrying the steel roller is applied to the strings, it will be evident that the roller will

rotate as it is passed along the strings and in this manner avoid all scratching or scrap-

ing sounds and save the strings instead of

wearing them out. Wrapped strings in par-

ticular are more liable to wear rapidly with

the use of a solid guitar steel. By reversing

the guitar bar and placing the hard wood

edge against the strings, a more mellow and

beautiful tone will be produced, so that in

this manner the playing may be suited to

the character of the music and the fancy of

the player.

A slightly modified form of the guitar bar

is shown in Fig. 5. A steel roller 16 is, as

already described carried along the lower,

hollowed out edge of the body portion 10.

In this case, also the top edge of the body

portion is hollowed out to accommodate a

second roller 20 made of hard rubber, fiber

or hard wood. This roller is also carried

revolubly in the bearing plates secured to the

Having thus described the invention, what is claimed as new is:

1. As a new article of manufacture, a bar for stringed instruments consisting of a solid body of non-metallic material, said body being provided with a hard longitudinal edge rounded in transverse direction for contacting with the strings of the instrument.

2. As a new article of manufacture, a bar for stringed instruments said bar having a length sufficient to bridge across the strings and consisting of a solid body of non-metallic material, said body being provided

110

with a hard longitudinal edge rounded in transverse direction for contacting with the strings of the instrument, said body tapering in both directions from a substantially middle longitudinal line thereof.

3. As a new article of manufacture, a bar for stringed instruments consisting of a

body and a straight hard wood strip intimately united with and extending along one longitudinal edge of said body, said strip having a transversely rounded edge.

In testimony whereof I affix my signature.

EDWARD SULLIVAN. [L.S.]
